UNITED STATES PATENT OFFICE.

ELMER L. SCHUMACHER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

1,267,000.

Specification of Letters Patent. Patented May 21, 1918.

Application filed November 30, 1917. Serial No. 204,597.

To all whom it may concern:

Be it known that I, ELMER L. SCHUMACHER, a citizen of the United States, residing at Southbridge, in the county of 5 Worcester and State of Massachusetts, have invented certain new and useful Improvements in Ophthalmic Mountings, of which the following is a specification.

This invention relates to improvements in 10 ophthalmic mountings and has particular reference to an improved construction of what is commonly known as the Windsor type, that is to say a mounting having an inner metallic rim and an outer ornamental, 15 preferably non-metallic portion.

One of the leading objects of the present invention is the provision of a novel and improved construction whereby a non-metallic ornamental frame member may be readily 20 applied to ordinary constructions of metallic frames without the necessity of changes in the original construction of the frame and without adding additional parts to the frame itself.

25 A further object of the present invention is the provision of novel and improved means for firmly and securely retaining a supplemental frame member in position with respect to the main frame without 30 direct attachment or connection of the supplemental frame to the main frame.

35 A further object of the present invention is the provision of a novel and improved form of frame in which the supplemental portion may be readily removed from the main portion when desired, or in which the supplemental portion will remain in close engagement with the main frame portion both when in use and when the main frame 40 is opened for the insertion or removal of a lens.

45 Other objects and advantages of my improved construction should be readily apparent by reference to the following specification taken in connection with the accompanying drawings, and it will be understood that I may make any modifications in the specific details of construction shown and described within the scope of the appended 50 claims without departing from or exceeding the spirit of my invention.

Figure I represents a front view of a mounting embodying my improvements.

Fig. II represents a fragmentary enlarged perspective view of the rear face thereof. 55

Fig. III represents a fragmentary vertical sectional view of the construction illustrated in Fig. II.

Fig. IV represents a view similar to Fig. 60 III of a spring type of construction.

Fig. V represents a perspective view of the device shown in Fig. IV, as applied to the frame.

Fig. VI represents a sectional view of another modified form of my invention. 65

Fig. VII represents a view in elevation thereof.

In the drawings, in which similar characters of reference are employed to denote corresponding parts throughout the several 70 views, the numeral 1 designates the bridge of one of my improved mountings, which bears at each end the metallic lens frame 2, adapted to receive the lens 3, and provided with the end piece members 4, connected as 75 by the screw 5 which serves to hold the end pieces together and thus retain the lens within the frame 2 and at the same time the screw 5 may afford a pivot for the temple member 6. 80

Surrounding each of the metallic frame members 2 is a supplemental ornamental preferably non-metallic frame portion 7 having a central groove as at 8 into which fits the member 2. In the form of my invention illustrated in Figs. II and III for example, I have shown each end of the frame 7 as provided with the pair of connecting plates or wires 9 having their ends embedded as at 10 in the material of the frames, 90 and having their adjacent ends formed with aligned apertures adapted to receive the securing screw 11. 85

In the use of this form of my invention the supplemental frame 7 is fitted around 95 the main frame 2 and its ends brought into close engagement with the end pieces 4 when the apertures of the connecting members at each side will register and may have passed therethrough the fastening screws 100 11, which secure the plates together and thus firmly hold the supplemental frame in place around the main frame, although there is no direct connection between the main and supplemental frames. It is to be 105 noted, however, that in the form of the in-

vention illustrated in Figs. II and III, I have shown the end piece members recessed as at 12 to receive the connections 9, but it will be understood that this form of construction is particularly adaptable for use when frames are being put out new as an entirety, and that by slightly different bending of the members 9 they may substantially fit around the ordinary end pieces now on the market and thus allow my improved supplemental frames to be fitted onto present day commercial spectacles or eyeglasses without alteration or modification thereof.

In Figs. IV and V, I have shown a further form of my invention for accomplishing the same result. In this form I have shown the U-shaped clips 13 centrally embedded in and passing through the non-metallic frame 7 near each end and terminating in eyes 14, the eyes of the clips being connected at each side as by the springs 15, which may either fit around the end pieces or into the recess 12 therein, these springs in either instance holding the frames 7 around the metallic frames 2 under tension so that they will at all times be properly retained in place. On the other hand when it is desired to remove the frames 7 from the frames 2 it is merely necessary to stretch open the joint, which on account of the springs will have sufficient expansion to allow the supplemental frame to be snapped off the main frame, and when it is desired to insert a lens it is only necessary to loosen the screw 5 and separate the end pieces and the stretch of the spring will allow sufficient separation for changing the lens without necessity of removal of the supplemental frame.

In Figs. VI and VII, I have illustrated an extremely novel frame adapted to be constructed *de novo* for my improved mounting, as in this event there is embedded in each end of the frame 7 the head 16 of the split screw member 17, the two half screw members overlapping each other through the end piece sections 4, and being drawn into overlapped relation through rotation of the nut 18. It is to be noted that the members 17 are further provided with the shoulders 19 adapted in connection with the ends of the frame 7 to bear against the outer face of the end pieces so that as the screw sections are drawn into overlapped relation by rotation of the nut they will draw together the end pieces and tighten the main and supplemental frames around the lens to secure the several parts together. At the same time if desired the temple 6 may be pivoted on the half screw sections and in this form but a single fastening device at each end of the frames 7 serves to provide a pivot for the temple, a fastening means for the non-metallic frame, and a fastening means for the metallic frame, although in this, as in all other forms of my inven-

tion, the connection is between the two ends of the non-metallic frame and there is no direct securing of the ends of the non-metallic to the metallic frame or to the end pieces, though the proper connection of the two ends of the frames 7 will absolutely prevent disengagement of the frames 7 from the metallic frame 2 without severe distortion of the metallic frame.

It will, of course, be understood that not only is the form of my invention shown in Fig. VI adapted to lock the end piece members 4 together, even though the screw 5 be removed, but similarly in all other forms illustrated if the tension of the springs be sufficient they will hold the parts together without connection of the end pieces.

In connection with the form illustrated in Fig. II it is not necessary in an ordinary frame that the connections be placed on both sides of the joints of the ends of the frame member 7, but if desired the front cross member or connection may be dispensed with and the rear one only used, thus making a more slighty mounting when same is viewed from the front.

I claim:

1. An attachment for an ophthalmic mounting comprising a split non-metallic rim member having an interior groove to receive the mounting and means connecting the ends of the attachment independent of the mounting.

2. The combination with a spectacle mounting having endpiece members projecting outwardly therefrom, of an attachment for the mounting in the form of a split rim having its ends spaced to receive the endpiece therebetween, and means independent of the endpiece for connecting the ends of the attachment to each other.

3. An attachment for an ophthalmic mounting comprising a relatively non-resilient split supplemental frame member and resilient means connecting the ends of the frame member.

4. An attachment for ophthalmic mountings comprising a supplemental composition rim member interiorly grooved to fit the mounting and split at one side, and a resilient or spring connecting device drawing the ends of the attachment toward each other to retain the device in position on a frame.

5. In an ophthalmic mounting, the combination with a lens of a fitting projecting therefrom and a supplemental frame for the lens having a central groove and a recess receiving the projecting portion of the fitting, and a securing device for the supplemental frame secured to the opposite sides of the recess thereof and spanning a fitting substantially as and for the purpose described.

6. The combination with an ophthalmic

mounting including a lens having a fitting projecting therefrom, of a supplemental frame encircling the lens, said frame being split and having its termini abutting the fitting, and a fastening device for the supplemental frame spanning the fitting and directly securing the termini of the supplemental frame to each other.

7. A device of the character described 10 including a main frame and split supplemental frame, said supplemental frame having a groove to receive the main frame and means for directly connecting the ends of the supplemental frame to secure the same 15 in position.

8. The combination with a main frame, of a split supplemental frame embracing the main frame, anchors embedded in the terminal portions of the supplemental frame, said anchors having projecting portions and said projecting portions being united to each other to retain the supplemental frame in position on the main frame. 20

In testimony whereof I have affixed my signature, in presence of two witnesses. 25
